UNITED STATES PATENT OFFICE.

MORLEY PUNSHON REYNOLDS, OF CLEVELAND, OHIO, ASSIGNOR TO THE W. S. TYLER COMPANY, OF CLEVELAND, OHIO, A CORPORATION OF OHIO.

SCREENING APPARATUS.

1,333,219.

Specification of Letters Patent. Patented Mar. 9, 1920.

Application filed April 15, 1918. Serial No. 228,561.

To all whom it may concern:

Be it known that I, MORLEY PUNSHON REYNOLDS, a citizen of the United States, and a resident of Cleveland, county of 5 Cuyahoga, and State of Ohio, have invented a new and useful Improvement in Screening Apparatus, of which the following is a specification, the principle of the invention being herein explained and the best mode 10 in which I have contemplated applying that principle so as to distinguish it from other inventions.

The present invention, relating, as indicated, to screening apparatus is more particularly directed to the provision in apparatus to be used for graduating sand, ore, stones and the like of means adapted to increase the resilience and the life of the screen and hence increase the capacity of the 20 screen. It has but recently been recognized that the tonnage capacity of a screen depends to a very large extent upon the degree of tension of the screen and upon the uniformity of its tension across the entire 25 surface of the screen cloth. If the screen is not tensioned to the proper degree, it cannot be vibrated to any considerable extent, and if the tension is not uniform then the screen will sag and channels will form; 30 down which will flow the greater part of the material, in this way causing the material to wear out very fast at these channels.

It is customary to vibrate screens by means of bars attached to the screen surface at regular intervals, these bars usually bearing hammer posts, which are intermittently struck. In this way it is possible for a single blow to cause the vibration of the screen for its entire length, but I have 40 found that the vibration of the screen is restricted and damped by the lack of resilience and resistance to movement of the bars attached to the screen for receiving the blows.

45 It is obvious that no matter how tightly tensioned a screen surface may be, it cannot vibrate freely under a blow if it is held back by a non-resilient and relatively inflexible member in the form of a heavy bar extending entirely across the screen and attached to the same at a number of points.

50 The natural effect of such a bar is to dampen the vibrations and to increase very much the resistance of the screen to a bolt. One 55 important object of the present invention

is to provide means that will not only not dampen the vibration of the screen, but will positively assist and increase the vibration. To the accomplishment of the foregoing and related ends, said invention, 60 then, consists of the means hereinafter fully described and particularly pointed out in the claims.

The annexed drawing and the following description set forth in detail certain 65 mechanism embodying the invention such disclosed means constituting, however, but one of various mechanical forms in which the principle of the invention may be used.

In said annexed drawing:—
70 Figure 1 is a plan view of the screen surface, to which is attached a single longitudinally extending bar for carrying the impact posts; Fig. 2 is an end view of the same; Figs. 3, 4, 5, 6 and 7 are transverse 75 sections of a screen and bar attached thereto taken as on the line a—a in Fig. 1, but showing various types of bars which I have found advantageous for the purpose desired.

In Fig. 1 there is shown a woven wire screen cloth 1, attached at either side to metal strips 2, which it is understood may be attached to suitable members in the framework of a screening machine. The 85 screen is ordinarily tensioned by any suitable means to effect a uniform and high tension in the screen surface, thus giving the screen great resiliency and ability to vibrate under impact. Extending longitudinally 90 of the screen surface 1 is an impact bar 3, which is ordinarily riveted or bolted to the screen by means of bolts 4 at a series of spaced points and which is free at either end so that this impact bar is carried solely 95 by the screen surface and is freely movable therewith. Mounted on the impact bar are impact posts 5 of which there may be two or more for receiving blows imparted thereto for vibrating the screen.

100 Impact bars for receiving the blows for vibrating the screen have ordinarily been constructed and mounted in the manner shown in Fig. 1, but have always been constructed, so far as I am aware, of ordinary strap iron of the usual character which had no resilience in any way proportional to the resilience of the screen. I have found that a very remarkable increase in the capacity of 105 a screen to graduate materials can be obtain- 110

ed by proportioning the weight, strength and resilience of these impact bars to the character of the screen and to the character of the material to be graded. The impact bars are first of course proportioned to the type of the screen itself and are formed of some flexible and resilient material, such as spring steel or tough elastic woods, which will have a resilience and a resistance to movement of approximately the same amount as the screen surface upon which they are being used. In the event that wood is used as a material for the flexible strips it will preferably be fastened to a strip of spring steel, although in some cases it may be used alone, as, for example, in the grading of flour or similar fine materials which are dry, and which do not tend to splinter or roughen the wood, as would be the case if wood strips were used with a coarse sharp material, such as many kinds of ores and the like:

In Fig. 3 I have shown impact bars, consisting of an upper bar 6 and a lower bar 7, of lighter character than the upper, both of which are bolted to the screen surface by bolts 8. In Fig. 4 I have shown a still lighter lower bar 9 which would be used with a screen cloth of lighter weight and smaller mesh than the screen cloth which is shown in Fig. 3. In Fig. 5 I have shown a single upper bar 11 bolted to the screen cloth, the bolts 12 being provided with washers or metal lugs 13 for preventing the nuts 14 from working into the screen cloth and pulling through. It is not essential that the strength of the resilient impact bars be proportioned to the character of the screen cloth, as I have found that a very efficient action can be secured by using a relatively light spring strip which will allow the screen cloth to vibrate freely without any appreciable resistance on the part of the strip, as is the case where soft iron is used.

In Figs. 6 and 7 there are shown wooden strips 15 and 16 disposed above and below a screen cloth 17 and bolted thereto in the manner already described, while in Fig. 7 a thin, highly resilient strip of spring steel 18 is interposed between the lower wooden bar 16 and the screen surface. It will be evident that other combinations of spring steel, resilient wood and other flexible materials may be used, depending upon the resilience and character of the screen surface and the material to be graduated.

The requirement of all of such combina-

tions of impact bars is that the composite bar, consisting of one or more strips of metal, wood, or other materials, must be flexible and highly resilient and should have approximately the same ability to vibrate and no greater resistance to movement than the screen cloth itself.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a screening device, the combination of a uniformly tensioned vibratory woven wire screen, and a vibratory bar mounted across and in contact with said screen, said bar being highly resilient and being adapted to vibrate said screen when distorted.

2. In a screening device, the combination of a uniformly tensioned vibratory woven wire screen, and a vibratory bar mounted across and in contact with said screen, said bar being of spring steel and being capable of vibrating freely with said screen.

3. In a screening device, the combination of a uniformly tensioned vibratory woven wire screen, and a vibratory bar mounted on the surface of said screen, and extending thereacross, said bar being of highly resilient material adapting it to vibrate said screen when distorted by means of the resiliency of the bar.

4. In a screening device, the combination of a uniformly tensioned vibratory woven wire screen, and a vibratory bar mounted on the surface of said screen, and extending thereacross, said bar being of highly resilient material adapting it to absorb the initial shock of a vibratory impulse, and to then transmit the same to all parts of said screen surface.

5. In a screening device, the combination of a uniformly tensioned vibratory woven wire screen, and a vibratory bar mounted on the surface of said screen, and extending thereacross, said bar being of highly resilient material adapting it to be considerably distorted under the initial shock of a vibratory impulse, said bar thereafter being adapted to transmit said impulse throughout said screen.

Signed by me, this 3rd day of April, 1918.
MORLEY PUNSHON REYNOLDS.
